ELECTRONIC ADAPTER FOR FACSIMILE-
COMPUTER SYSTEM

Robert E. Kalvitis, Fairport, N.Y., assignor to Xerox
Corporation, Rochester, N.Y., a corporation of New
York

Filed Mar. 20, 1967, Ser. No. 6,310

Term of patent 14 years

(Cl. D26—5)

FIG. 1

Des. 210,589

PAGE 2

FIG. 2

Des. 210,589

PAGE 3

FIG. 1 is a front perspective view of an electronic adapter for facsimile-computer system showing my new design with the monitoring panel in an open position;

FIG. 2 is a front elevational view thereof with the monitoring panel closed;

FIG. 3 is a rear elevational view thereof;

FIG. 4 is an elevational view taken from one side of FIG. 2;

FIG. 5 is an elevational view taken from the side opposite that shown in FIG. 4; and

FIG. 6 is a top plan view of FIG. 2.

I claim:

The ornamental design for an electronic adapter for facsimile-computer system, as shown.
